UNITED STATES PATENT OFFICE.

JOHN M. PHILLIPS AND ROBERT F. PHILLIPS, OF CARRICK, PENNSYLVANIA.

RUNNING-GEAR FOR MINE-CARS.

No. 882,534.

Specification of Letters Patent. Patented March 17, 1908.

Original application filed November 30, 1907, Serial No. 404,560. Divided and this application filed January 21, 1908.
Serial No. 411,969.

To all whom it may concern:

Be it known that we, JOHN M. PHILLIPS and ROBERT F. PHILLIPS, citizens of the United States, residing at Carrick, in the county of Allegheny and State of Pennsylvania, have invented certain new and useful Improvements in Running-Gear for Mine-Cars, of which the following is a specification.

This application is a division of application No. 404,560, filed Nov. 30, 1907.

This invention has relation to running gears for mine cars and relates in particular to the wheels and axles of running gears in which the wheel is confined in position on the axle by means of a linch pin.

It has been found in practice that the bore of a mine car wheel rotating on a stationary axle wears out sooner at the back of the wheel, that is, at that side of the wheel which is next to the car, than at the opposite side of the wheel. In order to obviate this uneven wear it is necessary to supply lubricating oil more freely to the rear end of the bore than to the front end of the same, and this has been accomplished by closing the front end of the bore, as by a cap made integral with the wheel or an attached cap, so that, as there is no escape for oil at the front of the wheel, all the waste oil escaping from the oil cavity of the wheel will flow between the inner end of the bore and the axle, thereby keeping this portion of the bore liberally lubricated.

The cap wheels above referred to, while they have some good features, the principle one of which has been indicated above, are objected to by some operators for the reason that the linch pin which confines the wheel on the axle is concealed from view, being usually arranged within the cap or at the back of the wheel, and is liable to become worn out or broken without attracting attention and to cause a serious wreck. For this reason the wheel in general use at coal mines is one with a straight bore having an axle of uniform diameter extending through the bore and a linch pin on the outer side of the wheel and, while the oil may escape at the front of the wheel, this form is preferred to the cap wheel, as the linch pin is plainly in sight and can be readily replaced if worn or broken.

Our invention has for its object the provision of a wheel and axle which will possess all the advantages of both the cap wheel and its axle and the ordinary wheel with the bore and axle of uniform diameter and the linch

pin on the outside of the wheel, and will also possess other advantageous features, while free from the objectionable features of both these types of wheels and in carrying our invention into effect we provide a wheel having a cap with a central opening of somewhat less diameter than the bore of the wheel and an axle having its outer end reduced in diameter to form a stub-axle to fit the central opening in the cap, the reduced portion of the axle being of sufficient length to protrude through the opening in the cap and beyond the outer face of the cap and pierced for the reception of a suitable linch pin or similar device to confine the wheel on the axle.

In the accompanying drawings: Figure 1 is a vertical transverse sectional view of a wheel and axle constructed according to our invention and as applied to an axle with an axle box. Fig. 2 is a top plan view of the axle shown in Fig. 1.

The wheel shown in the drawing and embodying our improved construction is of the type known as a self-oiling wheel and is a single piece of cast metal comprising the rim 1 the spokes 2 and the hub 3, the latter being formed with an oil chamber 4, having an oil inlet 5 controlled by a spring pressed valve 6. An opening 7 extends from the oil chamber 4 to the central bore or eye 8 of the hub and serves to permit passage of the oil from the chamber 4 to the bore or eye. The hub 3 is formed with an integral cap 9 on its outer side and this cap is formed with a centrally located hole 10 for the reception of the end of the axle as will be presently described. The axle, designated 11, is formed with a cylindrical portion 12 that fits snugly in the bore or eye 8 of the hub and the end 13 of the axle is reduced in diameter to such size that it will fit the hole in the center of cap 9. The end 13 of the axle is pierced at 14 to receive a linch pin 15 which serves to confine the wheel on the axle and a washer 16 is fitted on the end 13 of the axle between the linch pin and the end of the hub. The hub of the wheel is formed with a rearwardly extending sleeve 19 and an axle box 20 is carried by the car and is formed with a socket 21 into which the sleeve 19 extends, a ring of fibrous packing 22 being arranged in a groove 23 formed in the wall of the socket and serving to prevent the passage of dust at this point. A loose washer 24 is interposed between the end of the sleeve 19 and the bottom of the socket 21 to reduce friction and the axle in

the rear of this washer is square and fits in a square hole or socket in the axle box, the axle being held stationary and the wheel turning on the axle. The reduced end of the 5 axle which passes through the cap on the front of the wheel joins the cylindrical portion 12 by a shoulder 25 that bears against the inner surface of the cap and this shoulder divides with the sleeve 19 the end thrust and 10 wear so that the wheel and axle will run a long time without wearing enough to decrease the gage of the car.

We claim:

15 In running gear for mine cars, a wheel having a chambered lubricating hub, with an axle bore having a diminished outer end

piécing the face of the hub, the latter being formed with an integral cap through which said bore extends, and said hub having a cylindrical sleeve projecting from its inner face, 20 through which said axle also extends, in combination with an axle passing through the hub, and a box in which the said hub sleeve rotates.

In testimony whereof we affix our signatures, in presence of two witnesses.

JOHN M. PHILLIPS.
ROBERT F. PHILLIPS.
